HUMIDIFIER

Filed Oct. 8, 1928

UNITED STATES PATENT OFFICE

PIERRE LA ROUCHE, OF BIDDEFORD, MAINE

HUMIDIFIER

Application filed October 8, 1928. Serial No. 311,220.

My invention relates to carburation and more particularly to the humidifying of the gas for internal combustion engines. The advantages of a small amount of water vapor added to the gasified fuel have been long known and have been well demonstrated. While used to some extent, most automobile engines are operated without such a system. This has been, I believe, for two reasons. 5 First, most of the proposed installations have been rather expensive, and are not wholly satisfactory in meeting the varied conditions of motor operation. One cause of trouble has been lack of proper control of the water vapor with resultant extremes of too much or too little. This difficulty I have solved by the use of a system, automatic in character and capable of embodiment in apparatus of simple and inexpensive nature.

10 Such system and an illustrative apparatus, I will now disclose, the latter appearing in the accompanying drawings in structurally satisfactory form and operating in accordance with my invention.

15 20 In the drawings:

Fig. 1 is a diagrammatic indication of such an installation.

Fig. 2 a view of my tank with cover removed.

30 Fig. 3 a central section on line 3—3 of Fig. 2, and

Fig. 4 another section at right angles thereto.

In Fig. 1, I have indicated at D a conventional dash and at E an internal combustion engine fed through a manifold M from a carburetor C.

The humidifying chamber H may be a simple metal casing having a tight cover H'. 40 Through it passes a stem S shouldered and gasketed as at s and with a connection of any desired sort at S'. At its end S², it is threaded and fitted with a nut N, gasketed to make a tight joint. The chamber is provided with any convenient dash bracket as B.

The stem S within the chamber H is provided with rather small perforations so that when connected as by a line L to the manifold M, there is a suction within the tube S proportionate to the fuel demands of the engine.

The intake end of the line L is open to permit air to be drawn into the line by the suction of the engine. The admission of air into the line may be controlled by a manually operable valve V threaded into the open end of the line and disposed for convenient operation by the driver.

It has been proposed to draw moisture from tanks or through absorbent members that I believe that my invention is distinctly novel in its following aspects.

My invention contemplates the extension of the water by dispersion throughout an absorbent medium in the closed chamber H. A convenient and available moss well adapted to this purpose is the *Sphagnum cumbifolium*. The great advantages of such a medium and of this species in particular is that while holding the water in an extended state, it yields in mass readily to any reduction in pressure in the chamber H. It is to be noted that the stem S is shrouded in the moss and as soon as there is suction set up in the line L from the intake M, the water, and even the moss itself, is drawn against the stem S yielding a film of moisture which is broken up and taken in through the perforation P in the stem S. It will, therefore, be seen that my moistening system is at considerable variance from those that bubble air through a body of water or even those drawing air through a pad or sponge.

My chamber H is a closed chamber. There may be some air leakage but it operates by suction to squeeze or extract from the absorbent body just that small amount of moisture at the rate needed by the engine intake.

My apparatus is obviously simple and entirely automatic. The actual water demand is curiously low, indicating to my mind that the humidification needed is far less than heretofore provided for. While I have specified my moss as preferable for several novel reasons, my device may be operated by a sponge or other absorbent body. The shape of my container chamber may be varied and its parts elaborated. The form shown, however, has obvious commercial advantages to fill a popular demand.

What I therefore claim and desire to secure by Letters Patent is:

1. A humidifier for the intake of an internal combustion engine, comprising a casing, a body of moss in said casing adapted to maintain a body of water in extended state therein, and a vapor pipe passing through said casing and the moss therein, and connecting at one end with the intake of the engine, the opposite end of said pipe being open to the atmosphere externally of said casing and said pipe within the casing having an opening therein through which moisture from said moss may be drawn into the pipe by the suction of the engine whereby to humidify the air passing through said pipe.
2. A humidifier for the intake of an internal combustion engine, comprising a casing, a water-saturated material in said casing adapted to maintain a body of water in extended state therein, and a vapor pipe passing through said casing and the material therein, and connecting at one end with the intake of the engine, the opposite end of said pipe being open to the atmosphere externally of said casing and said pipe within the casing having a series of perforations therein through which moisture from said material may be drawn into the pipe by the suction of the engine whereby to humidify the air passing through said pipe.

In testimony whereof I affix my signature.
PIERRE LA ROUCHE.
